STOKER FURNACE OR HEATER

Frederick T. Agricola, Gadsden, Ala.

Application March 11, 1940, Serial No. 323,272

14 Claims. (Cl. 110—45)

My invention has relation to a novel construction and arrangement of the fire pot and fuel delivery duct of a stoker fed furnace or heater.

The object of my invention is to obtain a more efficient and effective combustion of the fuel and to reduce the heat losses to the stack which result from the present methods of stoker combustion in the furnaces.

The distinctive feature of my invention lies in the introduction of the fuel by a feed stoker so as to form a central mass in the bottom of the fire pot and the introduction of the necessary air for combustion in preheated form only to the marginal edge from the base up of the fuel pile, whereby a zone of intense combustion is maintained from the bottom of the fire pot walls upwardly while a relatively cool central zone is maintained through the fire pot and combustion chamber by reason of the fact that no air of combustion is supplied directly to the fuel in the center of the fire pot. By thus concentrating the combustion about the marginal edge of the fuel mass and delivering thereto an ample supply of preheated air, I intensify the combustion against all of the radiating walls of the furnace from the fire pot base up, and suppress or reduce the temperature in the center of the fire pot and combustion chamber where it would be the least effective since it would pass out more directly to the stack without additionally heating the furnace wall.

My invention is characterized by introducing an under feed of fuel through an inlet duct which extends up centrally into the fire pot and is imperforate so that no air combustion has access to the fuel entering the fire pot. I surround the fire pot wall with a perforate liner which rests below upon a bottom plate having only marginal ports for the inflow of the combustion air into the annular chamber defined between the fire pot and the perforate liner, the perforations in the liner admitting air to the marginal edge only of the fuel mass over the inlet duct so as to induce an intense combustion there while leaving its center relatively cool. In fact, in the practice of my invention, the intense outer heat penetrating into the fuel mass brings about a coking of the latter with a gradual giving off of its more volatile constituent, and these coke masses, responsive to the continued feed of fuel, tend to break apart on radial lines and to scale or fall off from the marginal edge of the fuel mass so that there is a continuous delivery of coke into the intense marginal combustion zone

lying between the fuel feed duct and the perforate liner in the fire pot.

My invention will be best understood by reference to the accompanying drawings which illustrate it in two embodiments, one being for a standard heating furnace, and the other for a stoker fed circulating heater, but both operate upon the same novel principle above pointed out.

In the drawings:

Fig. 1 is a view of a stoker furnace, broken away to show the furnace partially in elevation and partially in cross section.

Fig. 2 is a cross sectional view taken on the line II—II of Fig. 1.

Fig. 3 is a view in elevation of a circulating heater with its outer casing broken away to show the ash pit and part of the fire pot in elevation and the stoker and fuel feed compartments in section.

Fig. 4 is a cross sectional view taken on the line IV—IV of Fig. 3.

Fig. 5 is an enlarged vertical cross section taken through the fuel inlet duct and fire pot of the circulating heater.

Fig. 6 is a horizontal sectional view taken on the line VI—VI of Fig. 5.

Fig. 7 is a detail sectional view taken on the line VII—VII of Fig. 6, showing one of the ash and clinked dump doors in an end of the fire pot.

Similar numerals refer to similar parts throughout.

In the embodiment of my invention illustrated in Figs. 1 and 2, I show a conventional type of heating furnace having an outer casing 10, and an ash pit 11 seated in spaced relation on a base ring 12. The ash pit 11 is closed below by the bottom wall 13 and has a marginal top flange 15 upon which is supported, with a snug fit, the bottom end of the tapered fire pot 16. A bottom plate 17, with its marginal edge tapered to conform to the taper of the fire pot, fits snugly into the lower end of the fire pot to close it below except for a central opening, for the reception of the imperforate fuel inlet duct 18 and marginal ports 19 for the admission of air from the ash pit 11 to the fire pot. A tapered perforate liner 20, with its upper end flared over to abut the inner wall of the fire pot 16, rests on the plate 17 with its bottom edge just inside of the series of air ports 19. This liner is provided with a multiplicity of downwardly directed air jet ports 21 which extend all around the fire pot and substantially from top to bottom of the liner. The liner thus defines a pre-heating air chamber 22 supplied

through the ports 19 and which release the air through the ports 21.

The fuel inlet duct 18 is shaped to be passed down through the central opening in the plate 17 and has a marginal flange 23 which seats on the plate 17 while the walls of the duct below the shoulder fit snugly into the central opening in the plate 17. This heavy shoulder 23 may be cored as shown to lighten the casting, but it will be noted that the delivery end of the duct 18 above the plate 17 is imperforate and flares outwardly and rises approximately midway of the height of the liner 20. Fuel is supplied to the duct 18 through a pipe 25 by a feed screw 26, driven by any suitable mechanism, from any suitable source of supply and the screw acts to force an under feed of fuel upwardly through the imperforate duct 18 and its delivery end so as to produce a mass or center pile above the bottom within the fire pot.

The upper end of the fire pot 16 is annular and is flanged to receive the annular base of the combustion chamber 27 which is thus adapted to be turned thereon so as to present its door frome 28 and door 29 in position to face at right angles to the stoker feed pipe 25. The one piece radiator 30 seats on top of the combustion chamber also with an annular fit, and this is provided with the usual radiator clean out collar 31 and clean out door 32. A blower fan 33 delivers air through the pipe 34 into the ash pit 11 under any suitable manual or automatic control, not shown. In like manner the stoker may have any suitable manual or automatic control for its fuel feed.

In operation, having assembled the furnace in the manner described and started the feed of fuel and air, as the center of the fuel pile builds up above the delivery end of the duct 18, it forms, in the fire pot 16, a central mass of fuel which has no direct supply of air for combustion except to its marginal edge and which therefore will not burn freely over its center. As the feed of fuel proceeds, the mass of fuel falls or flakes over from the marginal edge of the pile above the duct 18 and assumes position between the flange 23 and the liner 20 and there it receives a constant supply of air, preheated by reason of its passage upwardly against the plate 17 and through the annular chamber 22 and the jet ports 21, and this air is projected downwardly, in a multiplicity of jets against the marginal edge of the fuel pile and produces there a marginal zone of intense combustion against the wall of the liner 20 and the fire pot 16, and this marginal belt of intensely hot gases flows upwardly along the walls of the combustion chamber, which is generally ribbed for the more efficient radiation of heat to the external air circuit, and thence passes into the radiator 30, leaving a relatively cooler zone maintained through the center of the combustion chamber and fire pot. It is my purpose to restrain the combustion at the center of the mass of fuel and to intensify the marginal combustion about this fuel mass. As a result of this I obtain an exceedingly efficient transfer of heat to the air commencing at the level of the fire pot base and continuing throughout its flow up through the furnace casing 10.

In Figs. 3 to 7 inclusive, I show my invention applied to what is generally called a circulating heater. As shown this heater comprises a base 40 on which is mounted a cabinet-like casing 41 surrounding and spaced from a heater comprising an ash pit 42, a fire pot 43, and a combustion

chamber 44, there being a door 45 in the casing giving access to the combustion chamber. The ash pit is closed below and has an air admission damper 46. In a lateral extension of the casing I form a downwardly tapered fuel chamber 47, 5 with a sloping top door 48, which chamber delivers the fuel into a shoe 49 where it is engaged by the stoker feed screw 50 and forced through the pipe 51 into the feed duct 52. The pipe 51 is closed at its outer end and screw shaft 50a 10 projects through suitable bearings in the outer wall 54 of the lateral extension cabinet and is squared so that a crank can be applied and the feed screw turned by hand directly if desired. The preferred manner of operation of the feed screw is to provide a ratchet wheel 55 fast on the screw shaft 53 and placed between the yoke arms at the base of a ratchet arm 56 carrying a pawl 55a engaging the ratchet 55. A pull lever 58 is attached to the upper end of arm 56 and 20 projects forwardly through the front wall 59 of the stoker extension and is provided with a hand grip by means of which it can be reciprocated to rock the arm 56 back and forth and turn the stoker feed screw 50. A coil spring 60 normally returns the ratchet arm to retracted position. The feed duct 52 is tapered downwardly and forms a flanged half circle cover over the delivery end of the pipe 51, the flanges being of such size that they will pass through the central opening in the plate 53 which seats on the lugs 54 at the top of the ash pit 42. The fuel dust is flared as in the construction shown in Fig. 1, and seats snugly in the center opening in the bottom plate 43. A perforate liner 61 seats on the plate 53 inwardly from its marginal ports 62 and at its upper edge bears against the fire pot wall, so that it forms a preheating air supply chamber 63 supplied with air by natural or forced draft through the ash pit 42 and ports 62, under control of damper 46, or other suitable air regulating means.

It will be noted, by reference to Fig. 6, that the upper end of the fuel duct 52 is surrounded by a cored downwardly flared flange 64, which at the front and back of the fire pot will rest on the plate 53 adjacent to the base of the liner 61. At the sides of the heater the base of the flange 64 is substantially spaced from the end walls of the liner and I form clinker cleaner openings 65, each of which receives a rocker door 66 fast on a shaft 67, by means of which the door can be turned to dotted position, Fig. 7, to dump the clinkers and ashes into the ash pit which has a suitable ash door 68. The damper 46 provides for the admission of air through the port 69 and is opened and closed responsive to a manual and automatic control mechanism, such as forms the subject matter of my companion application, Serial No. 191,157, and which comprises the control box 70 60 containing the thermostat control element. The manual control levers comprise the upright member 71, the cross shaft 72 and the front hand set 73. The gases of combustion pass off through the stack 74 in the manner well understood and 65 air has access through the base 40 to pass up freely between the jacket 41 and the heater walls and out through openings in the top of the heater casing.

The operation of the circulating heater is much 70 the same as that already described, the fuel hopper being filled and the feed screw actuator handle 58 manipulated to feed the fuel up into the fire pot and into position to burn marginally responsive to the inflow of heated air through the 75

liner 61 in the manner above described. If clinkers or ashes collect in the end zones on the bottom plate 53 they can be removed by actuating a pull rod 75 which projects through the end 5 of the wall of the casing and has a common crank connection 76 to each shaft 67 controlling a door 66 and thus both can be rocked at the same time from one end of the casing, it being understood that the cranks 76 are housed within 10 the casing.

While I have shown my invention in but two forms, it will be obvious to those skilled in the art that it is not so limited, but is susceptible of various other changes and modifications, with- 15 out departing from the spirit thereof, and I desire, therefore, that only such limitations shall be placed thereupon as are imposed by the prior art or as are specifically set forth in the appended claims.

20 What I claim is:

1. A stoker fed furnace comprising a fire pot having a bottom plate with marginal air ports and a center opening, a stoker feed pipe having an imperforate delivery duct passing through 25 said opening and projecting substantially above said bottom plate, a perforated liner surrounding the fire pot wall and adapted to engage the latter overhead and to rest on the bottom plate inwardly of its marginal ports, means to admit a 30 supply of combustion air below said bottom plate for preheated delivery in the combustion chamber only through said perforate liner, and means to feed fuel to said delivery duct.

2. A stoker furnace according to claim 1, in 35 which the perforated area of the liner extends from near the bottom plate to a level above said delivery duct.

3. A stoker furnace according to claim 1, in 40 which the delivery duct is formed with an outwardly and downwardly flaring skirt extending from its upper edge into engagement with said bottom plate in spaced relation to said center opening therein.

4. A stoker furnace comprising a lower air 45 chamber and a blower air delivery pipe entering same, a fire pot mounted on the air chamber and closed below by a bottom plate, an imperforate fuel delivery duct having a flaring discharge end fitted snugly into said center opening and extending upwardly above the same with an outwardly flared shoulder seated on the upper surface of said bottom plate, a metallic liner at 50 its upper end engaging the fire pot walls and at its base resting on said bottom plate and defining a marginal air chamber having communication with said lower air chamber through marginal openings in said bottom plate and having air delivery ports for supplying the preheated air for combustion marginally about the said fire pot, and a combustion chamber surmounting said fire pot and carrying the furnace door and frame.

5. A stoker furnace comprising a lower air 55 chamber having a stoker feed pipe and a blower air delivery pipe entering same, a fire pot mounted on said air chamber and closed below by a bottom plate, an imperforate fuel delivery duct having a flaring discharge end fitted snugly into said center opening and extending upwardly above the same with an outwardly flared shoulder seated on the upper surface of said bottom plate, a metallic liner at 60 its upper end engaging the fire pot walls and at its base resting on said bottom plate and defining a marginal air chamber having communication with said base through marginal openings in said bottom plate and having

downwardly inclined air delivery ports for supplying preheated air for combustion marginally about the said fire pot, and a combustion chamber surmounting said fire pot and carrying the furnace door and frame.

6. A stoker furnace comprising a lower air 10 chamber having a stoker feed pipe and a blower air delivery pipe entering same, a fire pot mounted on said air chamber and closed below by a bottom plate, an imperforate fuel delivery duct 15 having a flaring discharge end fitted snugly into said center opening and extending upwardly above the same with an outwardly flared shoulder seated on the upper surface of said bottom plate, a metallic liner at its upper end engaging the fire pot walls and at its base resting on said bottom plate and defining a marginal air chamber having communication with said lower air chamber through marginal openings in said bottom plate and having downwardly inclined air delivery 20 ports for supplying preheated air for combustion marginally about the said fire pot, and a combustion chamber surmounting said fire pot and carrying the furnace door and frame and rotatably mounted on said fire pot to allow for adjustment 25 of the door in any desired relationship to the fuel and air pipes.

7. A stoker fed heater comprising an outer 30 jacket having mounted therein in spaced relation a furnace base, a fire pot mounted on the base, a combustion chamber mounted on the fire pot, a plate forming the bottom of the fire pot and having marginal air ports in communication below with a source of air supply and having a central fuel opening, a stoker feed pipe for fuel entering 35 said base, an imperforate fuel delivery duct connected to said pipe and fitted into said opening in the bottom plate and projecting upwardly therethrough to define a flaring imperforate fuel support, a liner defining a narrow and substantially high marginal chamber for preheated air surrounding the walls of said fire pot inwardly of the air ports in said bottom plate, the said liner extending substantially above the delivery 40 nozzle.

8. A stoker fed heater comprising an outer 45 jacket having mounted therein in spaced relation a furnace base, a fire pot mounted on the base, a combustion chamber mounted on the fire pot, a plate forming the bottom of the fire pot and having marginal air ports in communication below with a source of air supply and having a central fuel opening, a stoker feed pipe for fuel entering 50 said base, an imperforate fuel delivery duct connected to said pipe and fitted into said opening in the bottom plate and projecting upwardly therethrough to define a flaring imperforate fuel support, a liner defining a narrow and substantially high marginal chamber for preheated air surrounding the walls of said fire pot inwardly 55 of the air ports in said bottom plate, the said liner extending substantially above the delivery nozzle, said nozzle having a marginal outward flared apron extending downwardly from its top edge into engagement with said bottom plate to 60 define a downwardly contracted fuel chamber between it and said liner.

9. A stoker fed heater according to claim 7, in 65 which the fire pot is laterally elongated and the flaring base on the delivery duct front and back extends downwardly into substantial juxtaposition to the liner in combination with end clinker discharge doors in the bottom plate between the fire pot end and the ends of said duct.

10. A heater in accordance with claim 7, in 70

which the heater jacket is formed at one side with an extension casing including a fuel hopper and a ratchet operating mechanism for the stoker feed screw with means externally operable to actuate said ratchet drive for the feed screw.

11. In a heater having an inner heating unit and an outer jacket surrounding said heating unit, the combination of an extension on one side of said jacket which forms a fuel hopper, a 10 stoker feed mechanism, a second extension on said jacket enclosing said fuel hopper and said feed mechanism, a cover for both of said extensions which when raised permits access to said fuel hopper, and manually operable means extending through said last mentioned extension whereby the stoker feed mechanism may be operated externally of the heater.

12. In a stoker fed heater comprising an inner heating unit having a fire pot and an outer jacket 20 spaced from the heating unit, the combination of a plate forming the bottom in said fire pot and having a central fuel opening and marginal air passages therein, an imperforate fuel delivery duct fitted through said opening, a perforated

liner seated on said plate and spaced from the fire pot walls to form a preheating chamber having communication below with said marginal ports for a supply of combustion air, an outwardly turned lip on the top of said liner adapted to engage the fire pot wall with a substantially air tight fit to close said preheating chamber at the top, means to admit a regulable air supply beneath said plate, and means to feed fuel through the delivery duct into the center of the fire pot. 10

13. A heater according to claim 11, in which said manually operable means comprise a feed screw shaft having a pawl and ratchet drive comprising a rocker arm, a pull rod extending through the jacket front to operate said air, and 15 spring means to retard said rod.

14. A stoker fed heater according to claim 7, in combination with clinker discharge doors in the bottom plate, and common means extending through the heater jacket for jointly and simultaneously opening and closing said clinker discharge doors. 20

FREDERICK T. AGRICOLA.
